CLAIM

The ornamental design for a luminaire, as shown and described.

DESCRIPTION

FIG. 1 Front, top, left perspective view;

FIG. 2 Left side elevational view;

FIG. 3 Right side elevational view;

FIG. 4 Front elevational view;

FIG. 5 Rear elevational view;

FIG. 6 Top view;

FIG. 7 Bottom view;

FIG. 8 Front, top, left perspective view;

FIG. 9 Left side elevational view;

FIG. 10 Right side elevational view;

FIG. 11 Front elevational view;

FIG. 12 Rear elevational view;

FIG. 13 Top view;

FIG. 14 Bottom view;

FIG. 15 Front, top, left perspective view;

FIG. 16 Left side elevational view;

FIG. 17 Right side elevational view;

FIG. 18 Front elevational view;

FIG. 19 Rear elevational view;

FIG. 20 Top view; and,

FIG. 21 Bottom view.

The broken lines in drawing 7 represent boundaries of the claim; all other broken lines in the drawings depict environment and form no part of the claim.

1 Claim, 21 Drawing Sheets
